UNITED STATES PATENT OFFICE.

CHARLES B. BISHOP, OF NEW YORK, N. Y., ASSIGNOR TO CONSOLIDATED DENTAL MANUFACTURING COMPANY, OF NEW YORK, N. Y., A CORPORATION OF NEW YORK.

HANDPIECE FOR DENTAL ENGINES.

1,381,697.

Specification of Letters Patent. Patented June 14, 1921.

Application filed April 4, 1916. Serial No. 88,838.

To all whom it may concern:

Be it known that I, CHARLES B. BISHOP, a citizen of the United States, and resident of the borough of Manhattan, in the city 5 and State of New York, have invented a new and useful Improvement in Handpieces for Dental Engines, of which the following is a specification.

My invention relates to an improvement 10 in handpieces for dental engines, and particularly handpieces used in that class known as all cord dental engines, with the object in view of providing certain arrangements whereby a convenient and positive mechanism is provided for properly adjusting the drill spindle in its bearings and for maintaining such adjustment.

Another object is to provide a case for 20 the handpiece which is of two-part construction, and hence strong, light and sanitary; and which case has, as an integral part thereof, a stud for the temporary attachment of the cross head.

A further object is to provide certain improvements in the form, construction and 25 arrangement of the several parts whereby the above mentioned and other objects may be effectively carried out.

A practical embodiment of my invention 30 is represented in the accompanying drawings, in which—

Figure 1 represents a side elevation of 35 the assembled handpiece with the cross head secured thereto,

Fig. 2 represents a vertical section taken in the plane of the line A—A of Fig. 1, looking in the direction of the arrows,

Fig. 3 represents a transverse section taken in the plane of the line B—B of Fig. 40 1, looking in the direction of the arrows, and

Fig. 4 represents a transverse detail section taken in the plane of the line C—C of Fig. 1, looking in the direction of the arrows.

The device has the customary head piece 45 or frame 1, with its projecting sleeve 1*, which head piece serves to carry the hand piece as a whole; the drill spindle 2 with its clutch mechanism 3, clutch operating rod 4, milled thumb wheel 5, and driving pulley 6; the said pulley being fixed against rotation on the spindle 2 by a set screw 7.

The particular construction and arrangement of these elements constitutes no part of my invention, and, as they are of well known and approved form, they will not be further described.

The body of the case is denoted by 8, and it consists of a single, tubular piece, which may conveniently be formed of machined 60 steel, suitably roughened on the exterior as at 9, to provide a sufficient hand grip for the operator. By making this of a single piece, I have departed from the former well established practice which was to constitute 65 this part of the case by telescopically associating a plurality of sections (generally three), the engaging extremities of which were complementarily tapered and flared for permitting the insertion of the one into 70 the other; the said parts being secured in position by some means, such as solder. In doing away with this somewhat complex method of manufacture, the case of my improved hand piece obtains qualities of lightness and strength which are very desirable.

Furthermore, it has been the former custom, in view of the fact that the points of union of the several sections were somewhat unsightly, to provide an exterior sleeve of 80 some material, such as hard rubber or fiber; the said sleeve serving to conceal said joints and, at the same time, act as a hand-grip for the user. This former arrangement had a distinctly objectionable feature on the 85 ground that it was less sanitary than was to be desired. It will be clear that the form of case which I have devised is not only provided with a surface which serves as a hand grip, but, by its integrality of the body 90 portion eliminates the requirement of any exterior covering.

The tool holding end of the hand piece has the customary tapered nose 10, which is secured in the end of the case 8 by soldering 95 or in any other convenient manner and serves as a bearing for the front end of the spindle; while the rear end of the latter is reduced in diameter and mounted in a cylindrical bearing 11, which is threaded into the 100 head piece 1, as clearly shown in Fig. 2. The inner end of the bearing 11 is flared so as to have a smooth surface engagement with the shoulder formed on the spindle 2.

by the reduction of its rear end, the said point of engagement being denoted by 12.

The body 8 of the case has a flange 13 at its rear end which abuts the head piece 1, while a hollow nut 14 slidably engages the exterior of the body 8 and the flange 13, the said nut having interior screw threads for engagement with exterior threads on the adjacent portion of the head piece 1, thus 10 serving to lock the case to the said head piece.

Reverting to the bearing 11, it will be observed that its threaded engagement with the head piece 1 renders it longitudinally 15 adjustable with respect to the hand piece as a whole, thereby providing means for adjusting the fit of the spindle 2 in its bearings 10 and 11. For the purpose of operating the bearing 11, a toothed or notched wheel 15 is provided at one end thereof, which may be reached by the operator's fingers. After the bearing 11 had been adjusted, it is locked 20 against movement by means of a clip 16 which is secured to the head 1 by a screw 17 and has a lug 18 fitted to engage the inter- 25 stices between the teeth on the wheel 15. The notches on the periphery of the wheel 15 amount, in effect, to calibrations.

The lug may be disengaged from the teeth 30 of the wheel 15 by loosening the screw 17 and slightly raising the clip 16.

With regard to this adjustment and its locking arrangement, it may be said that it has formerly been customary to merely provide 35 a device for turning the rear end bearing, together with a set screw for the purpose of securing the bearing in the desired adjustment. However, the point of engagement between the locking set screw and the bearing has been invisible, so that the operator was not sure whether he had really effectively locked the bearing in its adjustment 40 or not; and again, the operator would frequently neglect to turn down the set screw, owing to the fact that there was no difference 45 in its appearance whether it was tight or loose. Consequently, it was a fact of frequent occurrence that the spindle bearing would, in the course of operation, alter its position; thus failing to constitute a proper bearing surface for the spindle, with the result of undue noise in operation and wear on the parts.

By my improved arrangement, on the other hand, the locking engagement between the lug 18 and the wheel 15, is visible and positive, so that there is no chance of a failure to lock the bearing against movement and practically no chance of the operator 55 forgetting to engage the locking means.

A conventional form of right angle attachment is denoted by 19, which is provided with an open end 20 for engaging the hand piece in the customary manner. As a means 60 of locking this attachment against rotation

on the hand piece, a stud 21 is provided, which stud is integral with the body portion 8 of the case, and formed by striking outwardly a portion thereof. This stud is adapted to fit in a slot 22 in the hollow end 70 20 of the attachment 19, in the usual manner. Formerly, this stud was generally formed by threading a little screw into the proper part of the case 8. By my improvement, the end of cheapness and simplicity of 75 manufacture is not only obtained but the danger of the stud falling out is, of course, absolutely prevented. Moreover, inasmuch as the screw formerly used pierced the casting, the lubricating oil frequently leaked 80 out and oiled the fingers of the operator; a very disadvantageous feature, which is fully overcome by my said improvement.

The operation of the device will be apparent from the foregoing description, and I 85 desire it to be understood that various changes may be resorted to in the form, construction and arrangement of the several parts without departing from the spirit and scope of my invention; hence I do not intend 90 to be limited to the specific details herein shown and described except as they are mentioned in the claims.

What I claim is:—

1. In combination with the head piece of 95 a dental engine having a projecting sleeve and an exteriorly screw threaded portion, a hand piece comprising a case mounted on said sleeve and provided at one end with an annular flange arranged to abut said threaded portion, and a hollow nut adapted to engage said flange and threaded portion for locking the case to the head piece and sleeve.

2. In combination with the head piece of 105 a dental engine having a projecting sleeve and an exteriorly screw threaded portion, a hand piece comprising a unitary tubular case mounted on said sleeve and provided at one end with an annular flange arranged to abut said threaded portion, and a hollow nut 110 adapted to engage said flange and threaded portion for locking the case to the head piece and sleeve.

3. In combination with the head piece of a dental engine having a case removably secured thereto, a spindle rotatably housed in 115 said case, bearings in the case arranged to support said spindle, one of said bearings having a screw threaded engagement with the head piece, a calibrated wheel carried by 120 said bearing, and a clip removably secured on the head piece and provided with a V shaped lug overhanging said calibrated surface in position to enter one of the calibrations to lock the wheel and bearing in a pre- 125 determined position.

4. In combination with the head piece of a dental engine having a case removably secured thereto, a spindle rotatably housed in said case, a fixed bearing located at the outer 130

end of the case, a bearing having a screw threaded engagement with the head piece and longitudinally movable in the inner end of the case, a calibrated wheel carried by said bearing, and a clip removably secured on the head piece, a V shaped lug depending from said clip and overhanging said cali-

brated surface in position to enter one of the calibrations to lock the wheel and bearing in a predetermined position.

10

In testimony, that I claim the foregoing as my invention, I have signed my name this 31st day of March, 1916.

CHARLES B. BISHOP.
